UNITED STATES PATENT OFFICE.

NICOLAY NELSON, OF WAUKEGAN, ILLINOIS.

GARMENT-PRESSING MACHINE.

1,097,138.

Specification of Letters Patent. Patented May 19, 1914.

Application filed March 21, 1912. Serial No. 685,379.

To all whom it may concern:

Be it known that I, NICOLAY NELSON, a citizen of the United States, residing at Waukegan, in the county of Lake and State of Illinois, have invented certain new and useful Improvements in Garment-Pressing Machines, of which the following is a specification.

This invention relates to garment pressing machines in which great pressure is desired to be exerted at times on the garment or article to be pressed, although the degree of pressure may be varied to suit different conditions.

The objects of this invention are to provide a machine of this character in which the power may be furnished either by the operator or from some suitable source of power, but preferably the latter; to provide a power-driven machine in which the presser-iron may be caused to be quickly moved into pressing position by a simple action of the operator, and the presser-iron then held in pressing position for a predetermined time and then returned to normal inactive position without further action on the part of the operator, or the iron may be held in pressing position as long as desired by the operator.

Further objects of my invention are to provide a machine of this character, which is strong and substantial in construction and which will require comparatively little attention or adjustment in operation.

I accomplish these objects, and such other advantages as will appear hereinafter, by means of the machine shown in the accompanying drawings, in which:

Figure 1 is a side view of the same, parts being broken away or omitted for convenience in illustration, Fig. 2 is a sectional detail plan view showing the connections between the toggle link and presser arm lever, Fig. 3 is a rear elevation on an enlarged scale, parts also being broken away or omitted, Fig. 4 is a detail view showing the arrangement of a trip rod for a catch, Fig. 5 is a detail side view showing the principal automatic controlling or operating devices in normal or inactive position, and Fig. 6 is a similar view showing the parts in position when the machine is thrown into pressing action by the operator.

As shown in these drawings, 8 indicates a strong substantial frame upon which is mounted a presser table 9. The frame is

provided with an upwardly extending support 10, in which a presser arm lever 11, is pivoted at 12. The presser arm 11 is provided with a vertical shaft or pin 13, on which is mounted an adjustable presser arm 14, having at its outer end a screw 15 carrying the presser iron 16. The lever 11 is provided at its lower end with a cylinder 17, which is preferably made integral therewith, this cylinder being open at its front end and closed at the back end, as clearly shown in Fig. 2. A heavy compression spring 18 fits within the cylinder 17 and is engaged at the open end of the cylinder by a plunger 19, which engages with a yoke 20. A bolt 21 passes through the cylinder, plunger and yoke and is provided with a nut 22, whereby the tension of the spring may be adjusted.

In order that the machine may be operated by the action of the operator, I provide an extension 23 on the lower side of the cylinder 17, which is provided with a pin 24 fitting in a slot 25, in a link 26 which is connected with a bent foot lever 27. This foot lever is pivoted to a rod 28 in the frame of the machine, and has a pedal 29. It will be readily seen that when the operator presses down on the pedal the lower end of the lever 11 will be pressed backwardly or to the left as shown in Fig. 1 and will cause the presser iron 16, to engage with the garment or article placed on the table 9. A spring 30 is provided for holding the lever 27 in normal position and the slot 25 permits the lever 11 to be operated without moving the foot lever 27 when the machine is driven by power.

The power driven connections for the machine are as follows: The yoke or cross-piece 20 is provided with trunnions 31, which are connected by means of connecting rods 32 with hollow trunnions 33, at the upper end of a toggle block or link 34. A bolt 35 passes through the hollow trunnions 33 and serves to hold the ends of the rods 32 in position. The block 34 is cut away for a short distance at the center thereof, which exposes the central portion of the bolt 35. The lower rounded end of the toggle arm 34 fits in a socket in a bearing 36 supported in the lower part of the frame 8. The outer or relatively free end of the toggle arm is engaged at times by a crank arm 37, which arm hangs from a crank 38 in a crank shaft 39, which shaft is supported in bearings 40 at the rear part of the machine. This shaft is

driven by means of a gear 41, which meshes with a pinion 42 on a driving shaft 43, which shaft is supported in bearings 44 on the rear part of the frame. The shaft 43 5 may be driven in any desired manner, for instance by means of a pulley 45, this pulley being preferably made sufficiently heavy so that it will also serve as a fly wheel.

It will be readily seen that when the end 10 of the crank arm 37 engages with the free end of the toggle arm 34, the central portion of the bolt 35 being exposed to form a convenient bearing, it will press the toggle down and move the lower end of the lever 15 11 to the left, thereby causing the presser iron 16 to approach the table 9 to perform the pressing operation, and the spring 46 will tend to return the arm and connected parts to normal position. The pressing 20 action is controlled by regulating the movement of the arm 37 and the toggle 34. The toggle arm 34 is provided with lugs or projections 47 which are adapted to be engaged by catches 48 and 49 for holding the toggle 25 in depressed position, so that the presser iron may be held in depressed position for a predetermined time, or at the will of the operator. These hooks or catches are securely fastened to a bar 50, pivoted at 51 30 to the frame of the machine and extending inwardly a sufficient distance, or sufficiently weighted, so that the inner portion of the bar will out-weigh the outer portion and connected parts and tends to throw the 35 hooks or catches into engaging position. The catch strip or member 49, is extended upwardly a short distance and is provided at the top with a pivoted block 52, having a rod 53 extending therefrom, as best shown 40 in Figs. 5 and 6. This rod passes freely through a pin 54 extending out from the face of a weight or pendulum 55. This pendulum is pivoted at 56 to an arm or projection 57 from the bracket 36. A compression spring 58 fits over the rod 53 between the block 52 and pin 54. The weight or pendulum 55 is, at times, swung from side to side to accomplish certain controlling operations, and the spring 58 is only sufficiently 45 long so that when the weight is swung to the left as indicated in Fig. 5, the catches 48 and 49 will be swung out of the engaging position. The weight or pendulum 55 is provided with a rod or pin 59 which engages 50 with the crank arm 37 and, when the crank is turning, holds this arm out of engagement with the toggle bolt 35 until the operator desires to start the presser in action. This is accomplished by swinging the weight 55 55 over to the right as indicated in Fig. 6 which swings the pin 59 over a sufficient distance to permit the lower end of the crank arm 37 to engage with the bolt 35. This weight is swung by means of a rod 60 which extends 60 down through the frame and has its lower

end resting on the end of a foot lever 61, this lever being pivoted at 62 to a support 63 from any convenient part of the frame, preferably from the rod or shaft 28. The upper end of the rod 60 may engage directly 70 with the lower outer corner of the weight 55, but I prefer to have it engage with the lower bent end 64 of a bar 65 which is pivoted at 66 to the weight 55, and which extends upwardly through a bearing 66' and is provided adjacent to its upper end with a notch 67. This bar serves at times for holding the weight 55 in the position indicated in Fig. 6, so that the crank arm will be sure to engage with the toggle. For this 75 purpose, I provide a catch or pawl 68 which is pivoted to a block 69 so that it may swing upwardly to allow the end of the bar 65 to pass so that the pawl may engage with the notch 67 and will then hold it in raised position. The block 69 is securely fixed on a rod 70, supported in bearings 71, this construction being clearly shown in Figs. 3 and 4. The rod 70 is also provided with an arm 71' which extends forwardly and is pivotally 80 connected to a bent rod 72 which rod passes down and over the upper end of one of the projections 47 on the toggle 34 and engages with a bearing 73 on the frame. This arrangement is such that when the toggle 85 34 is up, the rod 72 will be raised, thereby raising the arm 71' and swinging the rod or shaft 70 so that the pawl 68 will be in engaging position. When the toggle 34 is pressed down, the weight of the arm 71 and 90 rod 72 will turn the shaft 70 and swing the pawl 68 up out of engaging position.

In order to swing the weight or pendulum 55 back to normal or inoperative position, I provide it with a tappet 74 which is pivoted thereto at 75 and rests against a stop 76 on the face of the weight. A spring 77 tends to hold the upper end of the tappet against such stop, the spring being sufficiently strong so that when the upper end 95 of the tappet is pressed to the left as shown in Fig. 6 it will swing the weight or pendulum 55 to the left. This tappet is adapted to be engaged by a cam or projection 78 on the crank shaft 39. The weight 55 is preferably prevented from swinging too far to the right by means of a stop 79, as shown in Fig. 6.

The machine may be driven by means of a belt (not shown) or in any other desired manner. Assuming that the driving shaft 43 is being driven at the proper speed, the operation of the machine is as follows: The operator places the garment or article to be pressed on the table 9 and then adjusts the presser iron 16, this adjustment being ordinarily sufficient to regulate the pressure desired. He then presses down on the outer end of the lever 61, which raises the rod 60 and throws the pendulum 55 over to the 100 105 110 115 120 125 130

right as indicated in Fig. 6. This also raises the bar 65 so that the notch 67 will be engaged by the pawl or catch 68, and will be held in raised position. It will be noted that, at such time, the toggle arm 34 is in its normal raised position as indicated in full lines in Fig. 4, which holds the catch 68 in proper position to engage with the notch 67. The movement of the weight or pendulum 55 causes the pin 59 to swing over a sufficient distance to allow the crank arm 37 to engage with the bolt 35 in the toggle arm 34, and as the crank arm moves down the toggle will be forced downwardly, which causes the connecting rods 32 to draw the lower end of the presser arm lever 11 back. This brings the presser-iron 16 into pressing engagement with the article on the table 9. Ordinarily, it is desirable to maintain the pressure for a greater length of time than would be obtained by a single downward movement of the crank arm 37, but it is also desirable to relieve the pressure after a short predetermined time. For this purpose the projections 47 on the toggle arms 34 are engaged by the catches 48 and 49, and the toggle is thereby held in depressed position, thus maintaining the pressure on the garment. It will be noted that when the toggle arm 34 is in such depressed position, the rod 72 is free to move downwardly so as to throw the catch 68 out of engaging position, and thereby release the bar 65. Then, as the crank shaft 39 continues its revolution the cam 78 will strike the tappet 74 and throw the weight or pendulum 55 to the left as indicated in Fig. 5. The pressure on the spring 58 is then sufficient so that the catches 48 and 49 will be thrown out of engaging position as soon as the toggle arm 34 is slightly depressed so as to relieve them. The crank arm 37 then moves down and engages again with the bolt 35 and presses the toggle down sufficiently to release these catches, then, as the crank arm moves upwardly, the toggle arm 34 follows it in its upward movement, until such toggle arm reaches its normal position, this upward movement of the toggle arm being caused by the springs 18 and 46. The weight 55 is now in such position that as the crank arm 37 again swings over and starts on its downward movement, it will be engaged by the pin 59 and deflected from the bolt 35 and may continue such movement without actuating the machine until the operator again presses on the foot lever 61, when such operation will be repeated. The return of the toggle 34 to raised position again raises the rod 72 and throws the catch 68 into engaging position. The principal object of this catch is to insure the holding of the weight 55 in proper position to cause the machine to operate when the operator presses on the foot lever 61. If the weight 55 were swung at such

time that the cam would immediately engage with the tappet 74, the weight would be thrown back and the crank arm prevented from actuating the toggle. The bar 65 and catch 68 insure the holding of this weight in proper position until the crank arm has actuated the toggle, when the weight is then free to be thrown over by the cam on the next revolution of the crank shaft 39. It will be noted that by means of this arrangement, the presser arm is swung down on the downward movement of the crank arm and is held in depressed position during one revolution, and is then released upon the next downward movement of the crank arm. If the operator desires to keep the pressure on for a longer time, he merely keeps his foot on the foot lever 61 which thereby holds the weight 55 in the position shown in Fig. 6, and the cam will throw the tappet 74 over without swinging the weight. Therefore, the catches 48 and 49 will remain in engaging position as long as the operator desires and will thereby continue the pressure until he again releases the foot lever.

It will be readily understood by those familiar with the art that my improved machine provides a simple and efficient mechanism for performing the various operations desired in pressing. It will also be noted that various changes may be made in the details of construction without departing from the spirit of this invention and, therefore, I do not wish to be limited to the exact construction herein shown and described except as specified in the following claims, in which—

I claim:

1. In a garment pressing machine, the combination with the presser arm lever, of a cylinder, a spring in said cylinder, a plunger engaging with said spring, a yoke engaging with said plunger, a toggle arm having one end mounted in the frame of the machine, connecting rods between the other end of the toggle arm and said yoke, a crank shaft mounted in the frame of the machine and a crank arm adapted to engage said toggle arm to cause it to swing and thereby actuate the lever.

2. In a garment pressing machine, the combination of a frame, a presser arm lever mounted in said frame, a spring pressed plunger engaging with the lower end of said lever, a toggle arm pivotally mounted in the frame, connections between said toggle arm and said plunger, a crank shaft mounted in said frame, a crank arm on said crank shaft adapted to engage with the toggle arm to press the same downwardly to swing said lever, and means for holding said toggle in depressed position whereby the pressure may be maintained.

3. In a garment pressing machine, the

combination of a frame, a presser arm lever pivoted in said frame, a toggle for actuating said lever, a crank shaft arranged above said toggle, a crank arm from said shaft 5 adapted to engage with said toggle, means for holding said crank arm normally out of engagement with the toggle, and means for permitting the crank arm to engage with the toggle when desired to actuate the pressing devices.

4. In a pressing machine, the combination of a lever, a toggle for operating said lever, a crank, a crank arm for actuating said toggle, a pivoted weight, a pin on said weight 15 for holding said crank arm normally out of engagement with the toggle, and means for swinging said weight to permit the crank arm to engage with the toggle.

5. The combination with a depending crank arm for operating a pressing machine, of a pendulum, a pin on said pendulum for holding said arm normally out of engaging position, means for swinging said pendulum to permit the arm to assume engaging position and means for throwing said pendulum back to its first position.

6. The combination of a crank shaft for driving a pressing machine, a depending crank arm from said shaft, a pendulum arranged adjacent to said crank arm, a pin on said pendulum for holding the crank arm out of engaging position, means whereby the operator may swing said pendulum to permit the arm to actuate the pressing devices, 30 means for temporarily holding said pendulum in such position, a tappet on said pendulum, and a cam on said crank shaft adapted to engage with said tappet to throw the pendulum back to its first position.

40 7. In a garment pressing machine, the combination of a toggle for actuating the pressing device, a crank shaft arranged above the toggle, a crank arm from said shaft adapted to engage at times with the toggle, a catch for holding the toggle in depressed position, a pivoted weight, connections between said catch and weight whereby the former will be thrown out of engaging position when the latter is swung 45 in one direction, a pin on said weight engaging with said crank arm, means whereby the operator may swing said weight beyond

the center to permit the crank arm to engage with the toggle, a spring held tappet on said weight and a projection from the 55 crank shaft adapted to engage with said tappet to throw the weight back to its normal position.

8. The combination with a pendulum for controlling the movement of a crank arm 60 which engages with a toggle for actuating a presser machine, of a bar having a notch in its upper end, a catch adapted to engage with said notch to hold the pendulum in adjusted position, a shaft on which said catch 65 is mounted, an arm on said shaft and a depending rod from said arm adapted to be engaged by the toggle whereby the catch will be thrown into engaging position when the toggle is raised and will swing out of engaging position when the toggle is lowered.

9. In a garment pressing machine, the combination of a frame, a presser table on said frame, a lever mounted in said frame, an adjustable arm pivoted to said lever, a 75 presser iron carried by said arm, a cylinder at the lower end of said lever, a spring in said cylinder, a toggle connected with said spring for moving the lever in one direction, a spring for moving the lever in the other 80 direction, a crank shaft arranged above the toggle a crank arm adapted to engage with said toggle to swing it down to actuate the presser iron, a catch for holding said toggle in depressed position, a pivoted weight 85 adjacent to said crank arm, a yielding connection between the weight and the catch whereby the latter will be thrown out of engaging position when the weight is swung to one side, a pin on said weight engaging 90 with the crank arm and holding the same normally out of engagement with the toggle, a foot lever and rod for swinging said weight to permit the crank arm to engage with the toggle, means for holding said 95 weight momentarily in such adjusted position, a spring held tappet on said weight and a cam on the crank shaft to engage with said tappet to throw the weight back to normal or first position.

NICOLAY NELSON.
